UNITED STATES PATENT OFFICE.

HENRY McDUFFIE, JR., OF FAYETTEVILLE, NORTH CAROLINA.

TIME GAS-VALVE.

SPECIFICATION forming part of Letters Patent No. 733,254, dated July 7, 1903.

Application filed December 29, 1902. Serial No. 137,030. (No model.)

To all whom it may concern:

Be it known that I, HENRY McDUFFIE, Jr., a citizen of the United States, residing at Fayetteville, in the county of Cumberland and State of North Carolina, have invented a new and useful Gas Cut-Off, of which the following is a specification.

My invention relates to gas cut-off devices, and has for its objects to produce a device actuated by a clockwork mechanism which may be set to cut off the gas at a certain predetermined time and which will when so set operate automatically to cut off the gas at the gas-meter, thus providing for extinguishing the lights in a store or the like at any predetermined hour during the night, the present invention being directed to the production of a simple, efficient, and inexpensive mechanism for attaining this end.

20 The invention comprises the details of construction and combination of parts more fully hereinafter described.

In the accompanying drawings, Figure 1 is a perspective view of the device. Fig. 2 is a 25 vertical sectional elevation of the same.

Referring to the drawings, 1 indicates a gas conduit or main which leads from the meter and supplies gas to the branch pipes of a system.

30 2 is a cut-off valve located in the pipe at the point adjacent to the meter and provided with the usual finger-piece 3, which projects horizontally therefrom. Secured to the stem of the cut-off valve is one end of a torsion-spring 4, which has its opposite end secured to the floor or other framework adjacent to the gas-main.

5 is a vertical finger of spring metal or the like secured to the floor and projecting upwardly therefrom at a point adjacent to the cut-off valve. This finger is bent to form an elbow or stop 6, which engages the finger-piece of the valve when the same is turned to open the valve, thus serving to maintain the same normally open and permit the flow of gas through the main. The upper end of the finger 5 is bent to form a horizontally-extending arm 7 for the purpose presently described.

50 8 indicates a clock of the ordinary alarm

type, which is suitably fixed to the floor or other framework at a point adjacent to the finger 5.

9 is a horizontally-movable rack mounted in slots 10, formed in the clock-easing. This 55 rack is provided on its upper edge with teeth which are engaged by a gear-pinion 11, which in turn is engaged and operated by the mechanism which actuates the clock-alarm, so that when the clock mechanism operates to sound 60 the alarm it will also set in motion the gear-pinion 11, which in turn will actuate the rack and move the same horizontally forward in the direction indicated by the arrow, and as the rack moves forward its end will engage 65 the arm 7 and force the stop 6 from beneath the finger-piece of the cut-off valve, thus permitting the torsion-spring, which is normally under tension, to rotate the valve-stem and close the valve, thus cutting off the supply 70 of gas at the meter and extinguishing the lights fed therefrom.

From the foregoing description it will be seen that I produce a device of very simple character which may be readily and inexpensively applied to any gas-main and which will automatically cut off the gas and extinguish the lights at any predetermined hour simply by setting the clock-alarm to sound 75 at the hour desired, which will cause the clock 80 to actuate the cutting-off mechanism in the manner above explained. In attaining these ends I do not limit myself to the details of construction herein shown and described, as various minor changes may be made therein 85 without departing from the spirit or scope of my invention.

Having thus described my invention, what I claim is—

1. In a gas cut-off, the combination with a 90 gas-main, of a cut-off valve therefor, a clock-work mechanism, a supporting-base therefor, a spring-finger extending upward from the base and engaging the valve to hold the same normally open, a rack carried and operated 95 by the clockwork mechanism for moving the finger out of engagement with the valve to release the latter, and means carried by the valve for automatically closing the same when released. 100

2. In a gas cut-off, the combination with a gas-main, of a cut-off valve therefor, a clock-work mechanism, a supporting-base therefor, a spring-finger extending upward from the base and engaging the valve to hold the same normally open, a rack carried and operated by the clockwork mechanism for moving the finger out of engagement with the valve to release the latter, and a spring carried by the

valve for automatically closing the same when released.

In testimony that I claim the foregoing as my own I have hereto affixed my signature in the presence of two witnesses.

HENRY McDUFFIE, JR.
